Primary Examiner — T Chase Nelson*Assistant Examiner* — Kelly L Gross(74) *Attorney, Agent, or Firm* — McMillan LLP(57) **CLAIM**

The ornamental design for an orthodontic distalizer, as shown.

DESCRIPTION

FIG. 1 is a perspective view of an orthodontic distalizer showing my new design;

FIG. 2 is a left side elevational view thereof;

FIG. 3 is a right side elevational view thereof;

FIG. 4 is a top plan view thereof;

FIG. 5 is a bottom plan view thereof;

FIG. 6 is a front elevational view thereof; and,

FIG. 7 is a rear elevational view thereof.

The broken lines of FIG. 7 illustrate portions of the orthodontic distalizer that form no part of the claimed design.
